(57) **CLAIM**

The ornamental design for a hall tree, as shown and described.

DESCRIPTION

FIG. 1 is a front perspective view of a first embodiment of a hall tree showing the new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right elevation view thereof;

FIG. 7 is a left elevation view thereof;

FIG. 8 is another front perspective view of a second embodiment of a hall tree showing the new design;

FIG. 9 is a front elevation view thereof;

FIG. 10 is a back elevation view thereof;

FIG. 11 is a top plan view thereof;

FIG. 12 is a bottom plan view thereof;

FIG. 13 is a right elevation view thereof; and,

FIG. 14 is a left elevation view thereof.

The broken lines in the drawings are for the purpose of illustrating portions of the hall tree that form no part of the claimed design.

1 Claim, 8 Drawing Sheets
